UNITED STATES PATENT OFFICE

162,079

BRACELET OR SIMILAR ARTICLE

Alfred Philippe, Scarsdale, N. Y., assignor to Tri-fari, Krussman & Fishel, Inc., New York, N. Y.

Application November 18, 1950, Serial No. 13,044

Term of patent 7 years

(Cl. D45—4)

To all whom it may concern:

Be it known that I, Alfred Philippe, a citizen of the United States of America, residing in Scarsdale, county of Westchester, and State of New York, have invented a new, original, and ornamental Design for a Bracelet or Similar Article, of which the following is a specification, reference being had to the accompanying drawing, forming part thereof.

Fig. 1 is a perspective view of a bracelet or similar article, showing my new design.

Fig. 2 is an edge view thereof.

I claim:

The ornamental design for a bracelet or similar article, substantially as shown.

ALFRED PHILIPPE.
